DETACHABLE SHOE HEEL

Adolph J. Sansonetti, Wakefield, Mass.

Application April 5, 1937, Serial No. 135,132

3 Claims. (Cl. 36—41)

This invention relates to a detachable metallic shoe heel provided with a detachable tread lift, and the main purpose of the present invention is to facilitate replacement of a worn out tread lift by a new one upon detachment of the heel from the shoe, the means for attaching the heel to the shoe and the means for attaching the tread lift to the heel being extremely simple and efficient, as well as permitting easy and expeditious removal of the heel from and attachment of the heel to the shoe and ready removal of the worn tread lift and application of a new tread lift when the heel is detached.

More particularly, the present invention contemplates the provision of a heel proper of hollow metallic form and open at the top, the means for securing the tread lift to the heel being accessible only through the top of the heel when the latter is detached from the shoe.

20. A specific object of the present invention is to provide a hollow metallic heel of light weight having simple and efficient means for detachably securing the same to the shoe so that a snug relation is provided between the heel and the shoe for presenting a sightly appearance when said heel is applied to the shoe.

The exact nature of the present invention will be more clearly apparent from the following description when considered in connection with the 30 accompanying drawing, in which:

Figure 1 is a fragmentary central longitudinal sectional view of a shoe provided with a detachable heel constructed in accordance with the present invention.

35. Figure 2 is a section on line 2—2 of Figure 1.

Figure 3 is a top plan view of the heel attaching plate forming part of the construction shown in Figures 1 and 2.

Figure 4 is a bottom plan view of the heel shown 40 in Figure 1, with the tread lift removed.

Figure 5 is a perspective view of the tread lift; and

Fig. 6 is a section on line 6—6 of Figure 3.

Referring in detail to the drawing, 5 indicates 45 the upper of a shoe and 6 the sole or bottom thereof. Detachably applied to the heel portion of the sole 6 is the heel constituting the present invention and consisting of a main heel member 7 of hollow metallic construction. This hollow metallic heel member has a flat bottom wall 8 and is open at the top, although provided along its side and rear upper edges with an inwardly directed flange 9, such flange being omitted at the front upper edge of the heel member 7 as shown 50 clearly in Figure 2. For the purpose of securely

detachably securing the heel member 7 to the heel portion of the shoe bottom or sole 6, I provide an attaching plate 10 having suitable apertures 11 for reception of nails or tacks 12, whereby said plate 10 is permanently secured flatly 5 against the under side of the heel portion of the bottom or sole 6. The plate 10 has the side and rear marginal edge portions thereof depressed as at 13 for engagement beneath the flange 9 of the heel member 7, the main portion of plate 10 10 which is not depressed and which is provided with the openings 11 being of a form and size to snugly fit within the space defined by the flange 9. This plate 10 is formed of spring metal so that the depressed marginal edge portion 13 thereof may 15 yield when the flange 9 is forced between the same and the bottom 6 of the shoe. This spring tension maintains a very intimate contact between the top of the heel member 7 and the bottom 6 of the shoe, and it will be apparent that application of 20 the heel member is had by simply sliding the same forwardly to effect the engagement of flange 9 over the depressed marginal edge portion 13 of plate 10 and between said marginal edge portion 13 and the shoe bottom 6. The removal of heel 25 member 7 is of course effected by sliding the same rearwardly or in a reverse direction, but means is provided to releasably secure said heel member 7 against this rearward sliding movement until intentionally released for that purpose. This 30 means consists of a depending extension 14 on the forward edge of plate 10 arranged to snugly engage the breast of the heel member 7 and provided at its lower end with an opening 15 for reception of a screw 16 having detachable threaded engagement in a threaded apertured portion 17 of the breast of heel member 7. By removing the screw 16, the heel member is released for being forcibly slid rearwardly and thereby detached from the shoe. A more snug engagement 40 of heel member 7 with the bottom of the shoe, and the desired amount of frictional engagement between the marginal edge portion 13 of plate 10 and flange 9 of heel member 7 may be had by providing the marginal edge portion 13 with upwardly pressed spaced portions 18 forming the only contacting surfaces between the marginal edge portion 13 of plate 10 and the flange 9.

As before stated, the main purpose of providing for detachment of the heel member 7 from the 50 shoe is to provide for access to the interior of said heel member 7 through the open top of the latter whereby fastening means for a detachable tread lift of heel member 7 may be manipulated to facilitate detachment of a worn out tread lift and 55

attachment of a new one. Such tread lift is preferably of special construction including a rubber, leather or composition bottom layer or plate 19 cemented to the under surface of a similarly shaped metallic plate 20 having a threaded central aperture 21 and provided with surrounding upwardly projecting spurs or prongs 22. The bottom wall 8 is provided with a central opening 23 adapted to receive a fastening screw 24 in position 10 for being threaded into the opening 21 of lift plate 20 for detachably securing the said lift to the bottom of the heel member 7, which screw 24 is accessible only from the interior of heel member 7 and through the open top of the latter. Also, the bottom wall 8 of heel member 7 has openings or 15 depressions 25 therein arranged for reception of the prongs or spurs 22 of lift plate 20 so that when the latter is firmly secured against the bottom of heel member 7, the tread lift will be effectively restrained against rotation about an axis coincident with the axis of the stem of screw 24. Accidental detachment of the tread lift from the heel member 7 is thus guarded against, and it will be apparent that the tread lift of the present 20 heel may be readily renewed with great facility and ease. For this purpose, it is simply necessary to remove the screw 16, detach the heel member 7 from the bottom of the shoe, remove the screw 24 so as to permit detachment of the tread lift, 25 replace the screw 24 so as to attach the new tread lift, replace the heel 7 on the bottom of the shoe and replace the screw 16 so that the heel is effectively secured in place. Being of metal construction, the heel member will be durable, and it can 30 be made of a desired weight by the use of suitable metal and in view of the hollow construction or form thereof.

It is believed that the construction and advantages of the present invention will be readily apparent from the foregoing description, and it will be understood that minor changes are contemplated such as fall fairly within the scope of the invention as claimed.

What I claim as new is:

45 1. A detachable heel comprising a hollow metallic heel member open at the top and provided along the sides and rear of its upper edge with an inwardly directed flange omitted at the front upper edge of said heel member, the breast wall 50 of said hollow heel member having a threaded opening, a sheet metal securing plate having its major central portion fastened to the under side of the shoe bottom in flat contact with the latter and provided with a downwardly offset marginal portion 55 at the rear and sides thereof, the inturned flange of the hollow heel member being engageable over the downwardly offset marginal portion of the securing plate by a substantially horizontal sliding movement of the heel with respect to said securing plate, an integral depending extension on the forward edge of said securing plate conforming to and engaging the breast wall of the hollow 60 heel member and having an opening registered with the threaded opening in the breast wall of said hollow heel member, and a screw passing through the opening in said extension and threaded into said threaded opening of the breast wall of the hollow heel member for preventing 65

rearward disengagement of the hollow heel member from the attaching plate.

2. A detachable heel comprising a hollow metallic heel member open at the top and provided along the sides and rear of its upper edge with an inwardly directed flange omitted at the front upper edge of said heel member, the breast wall of said hollow heel member having a threaded opening, a sheet metal securing plate having its major central portion fastened to the under side 10 of the shoe bottom in flat contact with the latter and provided with a downwardly offset marginal portion at the rear and sides thereof, the inturned flange of the hollow heel member being engageable over the downwardly offset marginal portion 15 of the securing plate by a substantially horizontal sliding movement of the heel with respect to said securing plate, an integral depending extension on the forward edge of said securing plate conforming to and engaging the breast wall of the 20 hollow heel member and having an opening registered with the threaded opening in the breast wall of said hollow heel member, and a screw passing through the opening in said extension and threaded into said threaded opening of the breast 25 wall of the hollow heel member for preventing rearward disengagement of the hollow heel member from the attaching plate, said attaching plate being of spring metal and having its downwardly offset marginal portion tensioned to cause snug 30 engagement of the upper end of said hollow heel member with the bottom of the shoe.

3. A detachable heel comprising a hollow metallic heel member open at the top and provided along the sides and rear of its upper edge with an inwardly directed flange omitted at the front upper edge of said heel member, the breast wall of said hollow heel member having a threaded opening, a sheet metal securing plate having its major central portion fastened to the under side of the shoe 40 bottom in flat contact with the latter and provided with a downwardly offset marginal portion at the rear and sides thereof, the inturned flange of the hollow heel member being engageable over the downwardly offset marginal portion of the 45 securing plate by a substantially horizontal sliding movement of the heel with respect to said securing plate, an integral depending extension on the forward edge of said securing plate conforming to and engaging the breast wall of the hollow 50 heel member and having an opening registered with the threaded opening in the breast wall of said hollow heel member, and a screw passing through the opening in said extension and threaded into said threaded opening of the breast 55 wall of the hollow heel member for preventing rearward disengagement of the hollow heel member from the attaching plate, said attaching plate being of spring metal and having its downwardly offset marginal portion tensioned to cause snug 60 engagement of the upper end of said hollow heel member with the bottom of the shoe, the downwardly offset marginal portion of said attaching plate having spaced upwardly pressed portions engaging the underside of the inwardly directed 65 flange of said hollow heel member.

ADOLPH J. SANSONETTI.
